UNITED STATES PATENT OFFICE.

FRANK M. SCHAEFER, OF CHICAGO, ILLINOIS, ASSIGNOR TO JAMES LYNN, OF WABASH, INDIANA.

ERASER-CLEANER.

1,399,888.

Specification of Letters Patent. Patented Dec. 13, 1921.

Application filed September 19, 1918. Serial No. 254,849.

To all whom it may concern:

Be it known that I, FRANK M. SCHAEFER, a citizen of the United States, and a resident of the city of Chicago, in the county of

5 Cook and State of Illinois, have invented certain new and useful Improvements in an Eraser-Cleaner; and I do hereby declare that the following is a full, clear, and exact description of the same, reference being 10 had to the accompanying drawings, and to the numerals of reference marked thereon, which form a part of this specification.

This invention particularly pertains to an improved type of a cleaning machine adapted to loosen up and thoroughly clean the felt pads or brush members of blackboard erasers and similar articles.

15 It is an object of this invention to construct a felt eraser cleaner adapted to remove dust from felt blackboard erasers and blow said dust into a bag.

20 Another object of the invention is to provide a cleaning machine wherein a rotatable brush is equipped with rows of beater members adapted to loosen up the felt on felt erasers to permit the brush bristles to remove the dust therefrom.

25 It is also an object of the invention to construct a cleaning machine for felt blackboard erasers, said machine having a mechanism for simultaneously operating a fan and a brush mechanism to remove dust from felt erasers.

30 A further object of this invention is the construction of an eraser cleaner wherein a cylindrical brush is provided with centrifugally acting members adapted to strike against the felt portion of an eraser to loosen up the felt to permit removal of the dust 35 therefrom by the brush bristles.

40 It is furthermore an object of this invention to provide a gear operated fan and brush mechanism adapted to thoroughly remove chalk dust from felt blackboard erasers which are moved through a guide channel over said brush mechanism.

45 It is an important object of this invention to construct a felt eraser cleaning machine of simple and effective construction 50 adapted to be manually operated to cause a brush and fan to remove dust from felt erasers.

55 Other and further important objects of this invention will be apparent from the dis- closures in the drawings and specification.

The invention (in a preferred form) is illustrated in the drawings and hereinafter more fully described.

On the drawings:

Figure 1 is a top plan view of an eraser 60 cleaner embodying the principles of this invention.

Fig. 2 is a top plan view of the interior of the device with the casing removed.

Fig. 3 is a sectional view taken on line 65 3-3 of Fig. 1, showing parts in elevation.

Fig. 4 is a transverse section taken on line 4-4 of Fig. 3.

Fig. 5 is an enlarged detail sectional view taken on line 5-5 of Fig. 3. 70

Fig. 6 is a section taken on line 6-6 of Fig. 5, with parts shown in elevation and parts omitted.

Fig. 7 is a sectional view taken on line 75 7-7 of Fig. 1.

Fig. 8 is a detail section taken on line 8-8 of Fig. 2, showing a fragmentary portion of the dust bag attachment.

Fig. 9 is an enlarged fragmentary detail section showing the method of attaching the 80 casing to the base member.

As shown on the drawings:

The reference numeral 1, indicates a base member or floor having the upper peripheral edge cut away to afford a groove 2. The 85 base 1, is made of wood or any other suitable materials and is supported by short legs or supports 3. Securely mounted upon the top and near one corner of the base 1, is a standard or bracket 4, having bearing 90 sleeves 5 and 6, integrally formed on the upper end thereof. A short shaft or axle 7, is journaled in the bearing sleeve 5, and has removably engaged on the outer extending end thereof a crank 8, provided with a knob 95 or handle 9. Keyed or otherwise secured upon the inner end of the shaft 7, is a large spiral gear 10, which meshes with a spiral pinion or small gear 11, keyed or otherwise secured upon the stub shaft 12, journaled in the bracket 4, below and parallel to the shaft 7.

Also keyed upon the stub shaft 12, to the inside of the pinion 11, and spaced therefrom is a large auxiliary spiral gear 13, which is in mesh with a small gear or spiral pinion 14, keyed upon a main shaft 15, having one end thereof journaled in the bearing sleeve 6, of the bracket 4. Removably secured to the bottom of the bearing sleeve 6, is a grease cup 16. 110

Securely mounted upon the base 1, opposite the bearing sleeve 6, is a tub, barrel or drum 17, open at the top and at its inner end. The tub 17, is closed at the outer end and is supported on said base 1, by means of an integral leg or support 18. A bearing sleeve 19, forms a part of the outer end wall of the tub 17, and rotatably supports the other end of the main shaft 15. A grease cup 20, is removably secured in an opening in the bearing sleeve 19, for the purpose of lubricating the bearing end of the shaft 15. A flange 21, is integrally formed on the inner open end of the tub 17, and secured to said flange by means of bolts 22, are the lugs 23, of a fan casing 24, having integral supporting legs 25, which rests upon and are secured to the base 1. The outer end of the fan casing 24, is open and registers with the open inner end of the tub 17. The end wall of the casing 24, is centrally apertured to permit the main shaft 15, to project therethrough. Disposed within the fan casing 24, is a disk or plate 26, provided with a passaged tub 27, which is secured to the main shaft 15, to permit rotation of said disk therewith. Integrally formed or rigidly secured at right angles to the disk 26, are a plurality of curved radial fan blades 28, which extend from the outer periphery of said disk to within a short distance of the center thereof. An outlet flue or pipe 29, is formed at the lower portion of one side of the fan casing 24, and has the outer surface of the end thereof ribbed or threaded as denoted by the reference numeral 30, to removably receive the neck or collar 31, of a dust bag or receptacle 32, engaged thereon.

A cylindrical brush member is rigidly secured upon the main shaft 15, within the tub 17, and embraces a sleeve 33, provided with a plurality of apertures on each side thereof within each of which is rigidly secured the inner end of a brush tuft 34. The two apertured sides of the sleeve are separated by two longitudinally disposed diametrically opposite ribs 35, which leave openings 36, forming two brush sections. Passaged end plates 37, are engaged on the main shaft 15, and abut the ends of the brush sleeve 33, and are held rigidly clamped in position by longitudinally disposed bolts or rods 38, which project through the openings 36, between the brush sections. Pivotally mounted upon each of the clamping bolts 38, between the end plates 37, are a plurality of centrifugally acting hook members or beaters 39, separated from each other by spacing rings 40. The outer hooked ends of said centrifugal beaters 39, are disposed in the circumference of the cylindrical brush, with the hooks on said rods disposed in opposite directions, as clearly shown in Fig. 5.

The mechanisms mounted upon the base 1, are inclosed by means of a box or casing 41,

the lower margin of which is flanged outwardly as denoted by the reference numeral 42, to permit the casing to rest in the base groove 2. The casing 41, is removably secured to said base 1, by means of screws 43, as shown in Fig. 9. Portions 44, of the side and end walls of the casing 41, are struck outwardly to afford ventilating or air openings 45. A large opening is provided in the front wall of the casing 41, to afford access to the mechanisms within the casing. The large opening is closed by means of a removable door 46, having a handle or knob 47, thereon which is adapted to be turned to move a locking tongue 48, into locking or release position with respect to said front casing wall. Each end wall of the casing 41, is provided with an opening to permit the bearing sleeve 19, and the crank 8, to project therethrough. Said casing 41, is also open at the top above the tub 17, and said opening is covered by a light metal casting which is secured to the casing 41, by screws or other suitable means, and comprises a channel guide 49, provided with a guide wall or back 50, and downwardly projecting lugs or projections 51, which serve to hold the casting in position transversely on the casing 41. The guide channel 49, is provided with an opening 52, through which the ends of the brush tufts 34, and the hook members 39, are adapted to project as the brush is rotated to permit the same to engage the felt flaps or strips 53, of a blackboard eraser 54, which is to be cleaned and which is moved transversely of the device in the brush guide holder or casting.

The operation is as follows:

With the device assembled as shown and described a blackboard eraser 54, or other similar article is adapted to be cleaned by placing the eraser upon the casting with the felt portion 53, resting upon the upper surface of the guide channel 49, and with the eraser back having one longitudinal edge thereof positioned to contact the guide wall 50. An operator guides and moves the eraser with the left hand across the opening 52, and at the same time turns the crank 8, with the right hand at any desired speed. Rotation of the crank causes the large driving gear 10, to rotate and thereby transmits an increased drive to the main shaft 15, through the pinions 11 and 14, and the gear 13. The rapid rotation of the main shaft 15, rotates the cylindrical brush thereby causing the ends of the bristles 34, to project upwardly through the opening 52, and engage the felt 53, of the eraser 54, to remove the chalk dust therefrom. The hook beaters 39, which form a part of the brush member are pivotally mounted upon the rods 38, and the rapid rotation of the brush causes said hook beaters to be thrown outwardly by centrifugal force to engage the 130

felt of the eraser to scrape the same so that the chalk dust held by the felt is loosened up to permit the bristles 34, to remove the same.

5 The fan 26—28, is rotated simultaneously with the brush and sets up a suction through the tub 17, and the fan casing 24, whereby the chalk dust removed from the felt eraser is drawn downwardly through the opening 10 52, and passes outwardly through the tube 29, into the dust bag or receptacle 32, where it is collected. When the bag is sufficiently full of chalk dust and other dirt which has been removed from erasers the bag may be 15 removed from the tube 29, and emptied.

Access to the mechanisms within the casing 41, is readily had by removing the door 46, by turning the knob 47, thereby disengaging the tongue 48, from behind the front 20 wall of the casing. The shaft 15, has the bearings ends thereof lubricated by grease from the grease cups 16 and 20.

The operation of the device is very simple and by merely turning the crank 8, simultaneous rotation of the fan and the cleaning brush is effected at an increased rate of speed due to the ratio of the driving gears and pinions. The centrifugal beaters or scrapers 39, of the brush mechanism are 25 mounted in longitudinal rows between the brush bristles 34, and serve to loosen the dust from the felt strips of an eraser so that the bristles may remove the same. Blackboard erasers and other similar articles may 30 be rapidly and thoroughly cleaned without permitting the dust and dirt removed therefrom from flying about.

I am aware that numerous details of con-

struction may be varied through a wide range without departing from the principles of this invention, and I therefore do not propose limiting the patent granted otherwise than necessitated by the prior art. 40

I claim as my invention:

1. An eraser cleaner of the class described 45 comprising a shaft, driving mechanisms therefor, a sleeve provided with end plates mounted on said shaft to rotate therewith, brush tufts mounted thereon in sections separated from one another, rods carried by 50 said end plates and disposed between said brush sections, and a plurality of beater members pivotally mounted on said rods.

2. An eraser cleaner embracing a rotatable shaft, an apertured sleeve secured thereon, brush bristles secured in said sleeve apertures, plates on said shaft adjacent the ends of said sleeve, rods connecting said plates and holding the same clamped against the ends of said sleeve, hooked beater members pivotally mounted on said rods, and spacers between said hooked members. 55

3. An eraser cleaner comprising a shaft, means for rotating the same, and a cleaning mechanism mounted on said shaft embracing brush members, rods separating the brush members, and centrifugally acting hook members disposed therebetween on said rods which extend parallel to the shaft. 60

In testimony whereof I have hereunto 65 subscribed my name in the presence of two subscribing witnesses.

FRANK M. SCHAEFER.
